(57) **CLAIM**

The ornamental design for an "electronic exhaustion indicator intended for use as a meter in conjunction with a vessel containing a liquid," as shown and described.

DESCRIPTION

FIG. 1 is a top plan view of an electronic exhaustion indicator intended for use as a meter in conjunction with a vessel containing a liquid;

FIG. 2 is a front elevational view thereof showing a portion of a vessel as environmental structure;

FIG. 3 is a rear elevation view thereof;

FIG. 4 is a right side view thereof, wherein the left side view is a mirror image of the right side view; and,

FIG. 5 is a bottom plan view thereof;

The broken line showing of broken lines is included for the purpose of illustrating non-claimed subject matter and forms no part of the claimed design.
